UNITED STATES PATENT OFFICE

137,465

DESIGN FOR AN ARC WELDING DEVICE

Clayton P. Nielsen, Chicago, Ill.

Application May 23, 1942, Serial No. 106,988

Term of patent 14 years

To all whom it may concern:

Be it known that I, Clayton P. Nielsen, a citizen of the United States, residing at Chicago, in the county of Cook and State of Illinois, have invented a new, original, and ornamental Design for an Arc Welding Device, of which the following is a specification, reference being had to the accompanying drawing, forming a part thereof.

In the drawing:

Figure 1 is a top plan view of an arc welding device showing my new design;

Figure 2 is a front elevational view thereof;
Figure 3 is a side elevational view thereof;
Figure 4 is a rear elevational view thereof; and
Figure 5 is a perspective view thereof showing the front and the one end.

I claim:

The ornamental design for an arc welding device, substantially as shown.

CLAYTON P. NIELSEN.
